UNITED STATES PATENT OFFICE

PANFILO TROMBETTA, OF MILWAUKEE, WISCONSIN, ASSIGNOR TO GENERAL ELECTRIC COMPANY, A CORPORATION OF NEW YORK

PALE SHADER FOR ALTERNATING CURRENT MAGNETS

Application filed July 28, 1930. Serial No. 471,307.

My invention relates to alternating current electromagnets and more particularly to the shading coils used therewith.

In alternating current electromagnets 5 humming or chattering of the armature is one of the difficulties which must be overcome. The means for accomplishing this result is the shading coil which is a short circuited coil placed in or near the pole face of 10 the electromagnet. The reversal of the flux through the electromagnet and its consequent building up and collapsing induces an electromotive force in the shading coil which results in the production of a flux which is out 15 of phase with the main flux. The result is that as the main flux passes through a zero value the auxiliary flux which is produced by the shading coil increases to a maximum value so that there is at all times a pull exerted upon the armature which materially 20 reduces or eliminates the chattering which would normally result.

It is well known that usually in the present forms of shading coils the out-of-phase 25 flux which is produced thereby is small and does not result in practically noiseless operation. Increasing the number of turns in the shading coil does not solve the difficulty because although the induced electromotive 30 force produced therein is increased the flux is not increased to any great extent due to the increase of the reactance of the shading coil which limits the out-of-phase current and hence the resulting out-of-phase flux which 35 maintains the armature in close contact with the electromagnet during periods of low main flux. Therefore, for a given magnet frame and a given exciting coil the greatest possible noiseless pull is practically fixed. Since this 40 pull is small, when a large noiseless pull is desired unusually large and expensive magnet frames are required.

Hence the principal object of my invention is the provision of an alternating current 45 electromagnet which is inexpensive and

which will practically eliminate chattering.

Specifically it is the object of my invention to provide an alternating current electromagnet in which the shading coils produce an out-of-phase flux which is greatly increased over usual present forms but without increasing to any great extent the reactance of the shading coil. 50

Other objects will appear hereinafter.

In the preferred embodiment of my invention I provide an electromagnet having a plurality of legs provided with faces having slots therein. The shading coils are placed in these slots and connected in series to cause an additive effect of the resulting induced 55 voltage. One of the poles is cut back or made shorter than the other, or others, the invention being applicable to two or three pole electromagnets, which results in increasing the induced voltage in the coil without increasing its reactance in the same ratio, 60 thereby resulting in an increased out-of-phase flux due to the increase of induced current in the shading coil. 65

In the accompanying drawings Fig. 1 70 shows a side view of one form of my invention; Fig. 2 shows the electromagnet and shading coil details of Fig. 1; Fig. 3 is a modification of my invention and Fig. 4 75 shows the electromagnet and shading coil details thereof; Fig. 5 is still another modification of my invention.

In Figs. 1 and 2 of the drawings, the electromagnet 10 is provided with slots 11 and 12. 80 Shading coils 13 and 14 are placed in the slots 11 and 12 and connected as shown at the rear of the electromagnet. The electromagnet is secured to a base 15 and is provided with a pivoted armature 16 cooperating therewith. It will be noted that a gap is provided between the armature 16 and the lower leg of the electromagnet when the armature 85 is in closed position. Mounted on one leg of the electromagnet 10 is the exciting coil 17 90

for energizing the electromagnet. A stop 18 is provided for the armature.

In operation, when exciting current passes through the coil 17 an alternating main flux results in the electromagnet 10 which results in moving the armature 16 into contact with the upper leg of the electromagnet.

As the flux collapses and builds up in the electromagnet 10 it induces in the shading, 10 coils 13 and 14 which are connected in series a voltage which is twice the voltage which would have been induced in only the one coil. This induced electromotive force results in a current through the coils in a direction to 15 cause a large out-of-phase flux for maintaining the armature closed during periods when the main flux passes through zero value. The inductance of the local circuits of the coils 13 and 14, more particularly of the portions of 20 the shading coils which are placed in the slots, depends upon the reluctance of the path through which the out-of-phase flux must pass. It will be seen that in the upper leg of 25 the electromagnet practically a closed magnetic circuit is provided in the electromagnet and the armature 16 with a resulting high reactance of coil 13. However, in the lower leg a gap between the lower leg and the armature results in an increase of the reluctance of the 30 magnetic path for the local circuit of the coil 14. Hence the reactance of the lower coil 14 is far less than that of the upper coil 13 but due to the fact that the same main flux cuts the lower coil 14 as cuts the upper coil 13 35 equal voltages will be produced in both coils. The result is that an electromotive force twice that which would be produced in one coil is produced but the reactance of the coil is increased in a much smaller ratio. This, of 40 course, results in a larger flow of current through the combined coils and a greater out-of-phase flux to hold the armature against its tendency to chatter.

In Figs. 3 and 4 is shown an E-shaped electromagnet making use of the same principles as those used in the form shown in Figs. 1 and 2. In this form the middle leg is cut back with the same result produced in the U-shaped coil, that is of increasing the induced 45 voltage in the shading coil while maintaining the reactance at a relatively low value. In the form shown in Figs. 3 and 4 the electromagnet 20 is mounted on a base 21 and provided with a pivoted armature 22. The exciting coil 23 which is mounted upon the 50 middle leg of the electromagnet furnishes the exciting current to produce the main flux in the magnet. The electromagnet 20 is provided with the slots 24, 25 and 26 in the pole faces 55 in which are mounted the shading coils 27 and 28. The coils are connected in series as can be clearly seen in the drawings so that the voltages induced therein have an additive effect in a manner similar to that in the form 60 shown in Figs. 1 and 2. The total flux passes

through the middle leg and divides between the two outer legs of the electromagnet so that as the flux collapses and builds up the portions of the coils 27 and 28 which lie in the slots 24 and 26 and the portions of these 70 coils lying on the outside of the middle leg are cut by the flux to produce the induced voltages therein. The portions of the coils lying in the slot 25 of the middle leg are cut by very little or no flux so that practically no 75 induced voltage results in this portion of the coils. The middle leg of the electromagnet is cut back to provide a gap between it and the armature to reduce the reactance, as explained above, of the portion of the shading 80 coils mounted thereon. That is, the reluctance of the magnetic path of the local circuits of the coils adjacent the outside of the middle leg is much greater than the reluctance of the magnetic path of the local 85 circuits of the coils in the slots in the outside legs. The result is that the induced voltage in the shading coils is increased in a greater ratio than the reactance of the coil. This is explained by the fact that the induced voltages in each coil are practically the same being cut by the same flux and are added whereas the reactance does not increase in the same ratio due to the difference in the 90 reluctance of the magnetic paths of the local 95 circuits of the shading coils. This results in a larger out-of-phase flux for maintaining the armature closed during operation of the electromagnet.

In Fig. 5 an electromagnet 30 is provided with the slots 31, 32, 33 and 34. Mounted in these slots are the shading coils 35, 36, 37 and 38. The modification shown in Fig. 5 may be comparable to two of the forms shown in Fig. 1 adjacent each other. The middle pole 105 of electromagnet 30 is cut back similar to the form shown in Figs. 3 and 4. The same operation takes place with this form of electromagnet.

Hence it will be seen that I have provided 110 a shading coil which is equally applicable to small and large electromagnets and which provides a greater out-of-phase flux than is normally provided thus producing a more 115 nearly noiseless operation of the electromagnet. This result is due to the ability to increase the induced electromotive force without increasing in proportion the reactance of the shading coil.

The embodiment of the invention illustrated and described herein has been selected for the purpose of clearly setting forth the principles involved. It will be apparent, however, that the invention is susceptible of being modified to meet the different conditions encountered in its use, and I, therefore, aim to cover by the appended claims all of the 125 modifications within the true spirit and scope of my invention.

What I claim as new and desire to secure by Letters Patent of the United States, is:

1. An alternating current electromagnet having an armature and a plurality of poles, an exciting coil for said electromagnet for producing a main flux therein, shading coils mounted in the faces of said poles for producing an out-of-phase flux and connected in series whereby the induced voltages in said coils are added, one of said poles being provided with a gap between it and the armature to effect a decrease in the reactance which said shading coils would normally have to materially increase the out-of-phase flux.
2. An alternating current electromagnet provided with a plurality of poles and having an armature, an exciting coil to produce a main flux in said magnet, slots in the faces of said poles, shading coils mounted in said slots and connected in series whereby the induced voltages in said coils are added, one of said poles being cut back from said armature to effect a decrease in the reactance which said coils would normally have, whereby the resulting out-of-phase flux is materially increased.
3. An alternating current electromagnet provided with a plurality of poles, pole shading windings placed in the pole faces and connected to cause additive effect of the induced voltage in said shading windings, and an armature cooperating with said electromagnet, one of said poles being shorter than the others to provide a gap between said armature and the pole face of said one pole.
4. An alternating current electromagnet provided with a plurality of poles, slots in the faces of said poles, shading coils placed in said slots and connected in series to cause an additive effect of the induced voltages therein, an armature cooperating with said poles, one of said poles being shorter than the others to provide a gap between said armature and the pole face thereof.
5. An alternating current electromagnet of U-shape, each leg being provided with a face with a slot therein, shading coils mounted in each slot and connected in series to produce additive effect of the induced voltages in said coils, an armature cooperating with the legs of said electromagnet one of said legs being shorter than the other to provide a gap between its face and said armature.
6. An alternating current electromagnet of U-shape, each leg provided with a pole face with a slot near the inner edge of each face, a shading coil in each slot, said coils being connected in series to cause the induced voltages therein to be added, an armature cooperating with the legs of said magnet, one of said legs being shorter than the other to provide a gap between said armature and said leg whereby the reactance which said shading coils would normally have is materially decreased.

7. An alternating current electromagnet of E-shape, each pole being provided with a slot in the face thereof, shading coils placed in said slots and connected in series to cause an additive effect of the induced voltages therein, an armature cooperating with said poles, the middle pole being shorter than the others to form a gap therebetween and the armature when the armature is in contact with said poles whereby the reactance which said shading coils would normally have is materially decreased.

In witness whereof, I have hereunto set my hand this 23rd day of July, 1930.
